UNITED STATES PATENT OFFICE.

NELSON E. MANN, OF NEW BRITAIN, CONNECTICUT, ASSIGNOR TO LANDERS, FRARY & CLARK, OF NEW BRITAIN, CONNECTICUT, A CORPORATION OF CONNECTICUT.

CURLING IRON.

Application filed March 23, 1922. Serial No. 545,978.

To all whom it may concern:

Be it known that I, NELSON E. MANN, a citizen of the United States, residing at New Britain, county of Hartford, and State of Connecticut, have invented certain new and useful Improvements in Curling Irons, fully described and represented in the following specification and the accompanying drawings, forming a part of the same.

10 This invention relates to curling irons.

It is the principal object of the invention to provide an improved curling iron in which the clip may be readily removed and repositioned by the user.

15 With this general object in view the invention consists in the combinations, details of construction and arrangement of parts which will first be described in connection with the accompanying drawing and then 20 more particularly pointed out.

In the drawing:

Fig. 1 is a view in side elevation of a curling iron with the clip in position for use.

25 Fig. 2 is a similar view with parts in cross section; and

Fig. 3 is a cross sectional view taken on the line 3—3 of Fig. 1.

Referring to the drawing, in the embodiment of the invention illustrated as an example, a curler 11 is mounted in a sleeve 12 of polygonal cross section which is set in a handle 13. The handle may contain an electric heating unit of suitable construction, a portion of a plug connection being indicated 35 at 14.

Associated with the curler 11 is a clip 15, arcuate in cross section to embrace the curler in the usual manner. This clip has a pivotal connection hereinafter described, whereby 40 it may be swung away from the curler. Associated with the clip, and conveniently formed integral therewith, is a handle 16 having at its end a button or thumb-piece 17.

In order that the curler may be used with 45 or without the clip, provision is made for the ready removal and replacement of the clip. There is provided a collar to which the clip 15 is connected and in structures embodying the invention to the best advantage this 50 collar is polygonal in cross section like the sleeve 12 and is dimensioned to slip or telescope over the latter. Although capable of various constructions, in that here illustrated as an example, pivotally secured to lugs 18 55 on the clip, by rivets 19 or the like, is a collar

20. This collar is hexagonal like the sleeve 12 and is enough larger to slip down over the latter with an easy fit.

The shape of collar 20 and sleeve 12 prevent the clip from turning when it is in assembled position and means is provided for normally holding it against longitudinal movement but in such manner as to permit easy removal. This may be accomplished by spring pressure and in structures embodying the invention to the best advantage, the spring utilized also serves to hold the clip clamped against the curler. Although capable of various constructions, in the embodiment illustrated, secured to the outer end of the clip handle 16 by the rivet 21 or the like that secures the button 17 to the handle is a bent bar spring 22. Opposite the free end of this spring, the wall of the collar 20 is cut away, as at 23, to permit the end of the spring to engage the sleeve 12. When the clip unit is in place the spring 22, bearing against the sleeve 12, normally holds the clip unit in position; it also holds the clip to its duty against the curler.

When the curling iron is used with the clip, the clip unit is held in position as above described. Pressure on the thumb-piece 17 causes the clip to open in the manner of a jaw, the spring 22 yielding, and rivets 19 serving as trunnions on which the clip pivots. Upon release of this pressure on the thumb-piece, the spring again causes the clip to be clamped against the curler.

When it is desired to use the curler without the clip, a slight force is applied to the clip handle to overcome the force of the spring and the collar 20 may be slid up the curler until the clip unit is free therefrom. To replace the clip in position for use, the collar 20 is slipped down the curler and over sleeve 12 and the end of spring 22 rides up onto sleeve 12 and again locks the unit in position. To regulate the relative position of the clip on the curler, stop means is provided. Although capable of various construction, in that here illustrated as an example, the rivets 19 extend far enough into the interior of collar 20 to serve as stops by engaging the end of sleeve 12 when the clip collar 20 is slipped down the sleeve 12. In replacing the clip unit no careful manipulation is necessary. Owing to the construction described, the relative angular position of curler and clip is im-

material, and the unit can be slipped into locked position by a single, simple movement.

What is claimed is:

- 5 1. In a device of the class described, and in combination, a handle, a curler extending therefrom, a removable clip for the curler, a handle associated with said clip, a collar connected with the clip to embrace the curler, the wall of said collar having a portion cut away to provide an opening, and a spring carried by the clip handle to extend through said opening when the clip is assembled with the curler, thereby to releasably hold the clip and collar in position. 45
- 10 2. In a device of the class described, and in combination, a handle, a sleeve of polygonal cross section therein, a curler mounted in said sleeve, a removable clip for the curler, a collar carried by said clip and of a cross section to telescope said sleeve, and yieldable means for normally holding said collar in position on the sleeve. 50
- 15 3. In a device of the class described, and in combination, a handle, a sleeve of polygonal cross section therein, a curler mounted in said sleeve, a removable clip for the curler, a collar pivotally connected with said clip and of a polygonal cross section to telescope said sleeve, the wall of said collar being cut away to provide an opening, a handle associated with said clip, and a spring carried by said clip handle, its free end extending into said opening to engage the sleeve when the clip unit is assembled with the curler, thereby to releasably hold the clip unit in position. 55
- 20 4. In a device of the class described, and in combination, a handle, a sleeve of polygonal cross section therein, a curler mounted in said sleeve, a removable clip for the curler, a collar of a cross section to telescope said sleeve, pivot members connecting said clip and collar and extending into the interior thereof to engage the end of said sleeve and serve as stops when the clip unit is assembled, and yieldable means for releasably holding the clip unit in position. 60
- 25 5. In a device of the class described, and in combination, a handle, a sleeve of polygonal cross section therein, a curler mounted in said sleeve, a removable clip for the curler, a collar of a cross section to telescope said sleeve, pivot members connecting said clip and collar and extending into the interior thereof to engage the end of said sleeve and serve as stops when the clip unit is assembled, and yieldable means for releasably holding the clip unit in position. 65
- 30 6. In a device of the class described, and in combination, a curler unit comprising a handle and a curler extending therefrom, and a removable clip unit comprising a clip to embrace the curler, a collar connected with the clip to fit over part of the curler unit, said collar having an opening therein, and a spring positioned to have its end engage the curler unit through said opening when the parts are assembled. 70
- 35 7. In a device of the class described, and in combination, a handle, a sleeve therein, a curler mounted in said sleeve, a removable clip for the curler, a collar with which the clip is pivotally connected, a stop member associated with said collar for engaging the end of said sleeve when the collar is telescoped thereon, and a spring for detachably holding the clip in position. 75

In testimony whereof, I have hereunto set my hand.

NELSON E. MANN.
